UNITED STATES PATENT OFFICE.

SAMUEL W. AKINS, OF DENVER, COLORADO.

REFRIGERATOR DISPLAY-CASE.

1,271,823.

Specification of Letters Patent. Patented July 9, 1918.

Application filed April 6, 1916. Serial No. 89,383.

To all whom it may concern:

Be it known that I, SAMUEL W. AKINS, a citizen of the United States, residing at the city and county of Denver and State of Colorado, have invented certain new and useful Improvements in Refrigerator Display-Cases; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in refrigerator display cases, my object being to provide a construction in which a circulation of air is maintained in such a manner that the temperature is kept low and approximately uniform throughout the entire case, notwithstanding the fact that in a device of this character the ice is located a considerable distance from, and occupies a surface slightly below that of the portions 25 of the case in which the articles to be displayed are located.

In my improved case the ice is located in the central portion of the case, the compartments or portions of the chamber occupied 30 by the articles, extending on opposite sides thereof and for a considerable distance beyond the compartment or location in which the ice is located. In cases of this character it is impossible to obtain the best results, 35 namely, to keep the temperature low and equable throughout the entire chamber, without special provision for obtaining a circulation of air from the central portion of the chamber where the ice is located, to the 40 opposite ends thereof, and back again to the ice compartment.

This circulation I obtain by spacing the drip pan in each end compartment or in each portion of the chamber adjacent the 45 central compartment where the ice is located, from the floor proper of the case, thus forming a space underneath the drip pan through which air may circulate below the pan, the outer extremity of this space in each 50 instance, communicating with a vertically arranged space between the outer end wall of the case and an interior partition spaced from the end wall, and perforated at suitably elevated points, to allow the air after 55 circulating below the drip pan and upwardly through the space at the end of the

case, to pass into the upper portion of the end compartment. Again, this air in turn will become cooled and move downwardly, after which it will again enter the space below the drip pan. In this manner the constant circulation of air through the refrigerating compartments of the case is maintained.

Having briefly outlined my improved construction, I will proceed to describe the same in detail, reference being made to the accompanying drawing in which is illustrated an embodiment thereof. In this drawing,

Figure 1 is a perspective view of my improved refrigerating display case, a portion of the outer wall being broken away, to disclose the interior of the structure.

Fig. 2 is a fragmentary vertical longitudinal section of the same.

The same reference characters indicate the same parts in all the views.

Let the numeral 5 designate my improved display case considered in its entirety and consisting of top, bottom, end and side walls inclosing a chamber having a central portion or compartment 6 and two end portions or compartments 7 arranged on opposite sides of and in communication with the central compartment. It will be understood that the divisions or planes of demarcation between the central compartment 6 and the end compartments 7 are imaginary rather than real. Nevertheless the term compartment is believed to be proper and certainly the most convenient term that can be employed in describing the structure. In the bottom of the central compartment 6 is located a pan 8 which slopes downwardly from its outer edges toward a central opening 9 from which leads a short drain pipe or nozzle 10 through which the water resulting from the melting of the ice cake 12 may pass. The outer edges of this pan are slightly below the upper surface of the drip pans 13 arranged on opposite sides of the ice pan, these drip pans being spaced from the bottom proper 14 of the case, in any suitable manner. This spacing of the drip pans from the bottom of the case, leaves 105 spaces 15 below the drip pans through which the air may circulate from the bottom of the central compartment 6 as indicated by the arrows in Fig. 2. As shown in the drawing, each drip pan 13 has the inner edge 110 of its bottom bent slightly downwardly as shown at 16 toward the bottom of the ice

pan, a space or opening 17 being, however, left to allow the air to enter the space 15 and circulate underneath each of the drip pans. The outer extremity of each space 15, communicates with the bottom of a vertically disposed space 18 which is formed between the end wall 19 of the case and an inner partition 20 which is spaced from the end wall in any suitable manner. The upper portion 10 of the partition 20 is provided with perforations 21 through which the air after circulating upwardly into the upper portion of each space 18, may return to the chamber of the case, this circulation being indicated by the arrows in Fig. 2 of the drawing. This air, after returning to the case, will again become sufficiently cooled to cause it to fall, after which it will again enter the inner extremity of the space 15, when its circulatory action will be repeated. In this way the constant circulation of air is kept up from the bottom of the ice compartment, outwardly and upwardly, and back into the upper portion of each end compartment, 25 thence through the end compartment to the center compartment, and again downwardly into the bottom of the ice compartment, where it commences another circuit. From this it will be understood that there will be 30 no dead air spaces within my improved case since there is a constant circulation of the air from the center or ice compartment, outwardly, upwardly, and back through the upper portions of the end compartments into 35 the center compartment.

Normal circulation through the provision chambers will not be interfered with, while heat taken up at the ends of the case within

the vertical spaces will be more quickly and thoroughly neutralized.

When desired the openings 21 may be closed by pivoted members 22.

Having thus described my invention, what I claim is:—

A refrigerator display case having a substantially, horizontally arranged bottom, a central ice compartment and an article-containing compartment arranged on each side thereof, the bottom of the ice compartment being inclined toward a central drain opening, the bottom of each article-containing compartment being provided with a drip pan which is downwardly inclined from its outer extremity toward the ice compartment, the bottom of the latter being slightly lower 55 than the upper surface of the drip pan, each drip pan being spaced from the bottom proper of the case, thus forming a bottom air space which is in communication at its inner extremity with the lower part of the 60 ice compartment, each article-containing compartment having at its outer extremity a vertical partition spaced from the end wall of the case to form a vertically disposed 65 air space which is in communication at its lower extremity with the outer extremity of the said bottom air space, the upper portion of the vertical air space being in communication with the upper portion of the adjacent article-containing compartment.

In testimony whereof I affix my signature, in presence of two witnesses.

SAMUEL W. AKINS.
